UNITED STATES PATENT OFFICE

JOSEF SCHULZ, OF BERLIN, GERMANY

TRAFFIC AIRSHIP OF THE RIGID TYPE

Application filed August 14, 1929, Serial No. 385,727, and in Germany June 7, 1929.

This invention is based upon the discovery that with traffic airships of the rigid type fractures of members of the horizontal rudder (for altitude steering), of the vertical rudder (for azimuth steering), and of the crank-shaft, can be obviated most securely and reliably if the weight of the airship is practically equal to the weight of the displaced air, that is to say, if the aircraft is 5 neither pretty much heavier than the air, like the present flying machines, or pretty much lighter than the air like the present airships.

Another means for the purpose in view, 15 and also forming a part, or parts, of the present invention is this that the body of the airship must be provided with fins so designed as to be adapted for use as supporting surfaces, as well as for use as break-winds, these fins being arranged at the sides 20 of the body in the horizontal middle plane thereof, and each of them being equipped with a driving propeller, as well as with a horizontal and a vertical rudder. I do not 25 mean to say that the filled airship, ready for use, must be indispensably accurately as heavy as the displaced air; there is a certain permissible deviation upwardly and downwardly which is a valuable feature concerning 30 the amount of gas required and the manoeuvring ability of the airship, especially on long journeys.

Throwing off of ballast and blowing off of 35 gas will hardly ever become necessary with airships of the present improved type, and it is as well out of the question that airships of this type will ever become a puppet of the wind.

The invention is illustrated diagrammatically and by way of example on the accompanying drawing, on which Figure 1 is a bottom-view of an airship designed according 40 to this invention, and Figure 2 is a front view thereof, drawn to a greatly reduced scale.

A denotes the body of the airship, and a 45 are the lateral fins which serve as supporting planes and are, in the example shown, so designed that the motors for driving the propellers can be housed in them. All fins

are located in the horizontal middle plane of the airship, or of its body respectively, and they may contain spaces or chambers not only for the motors and the attendants, but also for passengers, freight, and the like; 55 they act also as breakwinds and can be used in their entirety also in common acting as supporting planes in the case of a gliding flight.

There are, in the example shown, six 60 lateral fins and two front fins, and each of them is provided with a horizontal rudder c and with a vertical rudder d. b are the propellers pertaining to said six lateral fins and b¹ are the propellers pertaining to the two 65 front fins. The horizontal rudders of the two lateral fins at the rear are larger, as shown. Owing to the provision of a plurality of horizontal rudders and of vertical rudders 70 all of them are prevented from excessive strain as can arise, and arises not rarely, with the usual tail rudder known with airships of the types now in use. It is only due to the high-grade material that accidents due to 75 that excessive strain occur comparatively rarely. The tail rudder control members of airships of the usual design are subject to the entire amount of the stress due to axial compression, without any subdivision thereof, whereas in the present case such subdivision takes place owing to the provision 80 of that plurality of rudders, as shown and described.

It is also important for the safe and quick flight of the air-ship that the plurality of 85 propellers is located just in the middle plane of the body where their action is most effective in that their driving shafts lie just in said plane. The propellers b are the normally used driving propellers proper, whereas the propellers b¹ serve as spare propellers and are used generally only for manoeuvring purposes. This is true also of two bottom propellers e and e¹, of which e pertains to a separate motor housed in a front car i, and e¹ pertains to a separate motor housed in a rear car o. Between these cars is the main car B, of which nothing particular need be said, except that there may be cabins in it for passengers besides the main space at the 95 100

front for the officers of the airship, and that it is suspended below the metacentrum of the body. Behind the rear car *o* is provided a large vertical rudder *f* which is also provided partly as a spare rudder and partly for manœuvring purposes.

The motors in the cars *i* and *o* are preferably larger and, therefore, stronger than the motors in the fins. Of these latter motors those driving the first pair of the propellers *b* (the first pair behind the propellers *b*¹) are generally used for turning manœuvres. All propellers, or the propellers and their driving shafts, may be so designed that they can assume an oblique position with respect to the longitudinal axis of the body of the airship, that is to say, can form horizontal angles therewith. This arrangement is particularly suited for turning the airship practically around the vertical axis of its body, in which case diagonally located propellers are correspondingly adjusted.

I claim:

1. A traffic airship of the rigid type, comprising, in combination, a body and gas cells in it; a plurality of lateral fins distributed along both sides of the body in the horizontal middle plane thereof; propellers carried by said fins, also vertical and horizontal rudders attached to, and supported by, them and means for driving said propellers, the entire weight of the air ship being practically equal to the weight of the displaced air, substantially as set forth.

2. A traffic airship of the rigid type, comprising, in combination, a body and gas cells in it, a car suspended at its bottom; a plurality of fins distributed along the sides of said body in the horizontal middle plane thereof; propellers at the fronts of said fins and motors in the said fins for driving said propellers; a horizontal rudder at the rear of the fins and a vertical rudder at the outer side of the same, substantially as set forth.

3. A traffic airship of the rigid type, comprising, in combination, a body and gas cells in it, a plurality of hollow fins extending along the sides of said body and being regularly distributed thereat; propellers, horizontal rudders, and vertical rudders supported by said fins; means for driving said propellers; triangular fins at the front of the said body, and propellers and rudders attached also to these fins, substantially as set forth.

4. A traffic airship of the rigid type, comprising, in combination, a body and gas cells in it, a car suspended at its bottom; a plurality of fins distributed along the sides of said body in the horizontal middle plane thereof; propellers at the fronts of said fins; means for driving said propellers; triangular fins at the head of the body, and propellers and rudders carried also by these fins; a car arranged between these fins below the bottom

of the body, and a propeller and motor carried by this car, substantially as set forth.

5. A traffic airship of the rigid type, comprising, in combination, a body and gas cells in it, a car suspended at its bottom; a plurality of fins distributed along the sides of said body in the horizontal middle plane thereof; propellers at the fronts of said fins; means for driving said propellers; triangular fins at the head of the body, and propellers and rudders carried also by these fins; a car arranged between the rear fins below the bottom of the body, and a propeller and motor carried by this car, substantially as set forth.

6. A traffic airship of the rigid type, comprising, in combination, a body and gas cells in it, a car suspended at its bottom; a plurality of fins distributed along the sides of said body in the horizontal middle plane thereof; propellers at the fronts of said fins; means for driving said propellers; triangular fins at the head of the body, and propellers and rudders carried also by these fins; a car arranged between these fins below the bottom of the body, and a propeller and motor carried by this car, substantially as set forth.

7. A traffic airship of the rigid type, comprising, in combination, a body and gas cells in it, a car suspended at its bottom; a plurality of fins distributed along the sides of said body in the horizontal middle plane thereof; propellers at the fronts of said fins; a horizontal rudder at the rear of each fin, a vertical rudder at the outer side of each fin; three front propellers, means for carrying and means for driving them; a car arranged below the bottom and supporting the middle of said three propellers, substantially as set forth.

8. A traffic airship of the rigid type, comprising, in combination, a body and gas cells in it, a car suspended at its bottom; a plurality of fins distributed along the sides of said body in the horizontal middle plane thereof; propellers at the fronts of said fins; a horizontal rudder at the rear of each fin, a vertical rudder at the outer side of each fin; three front propellers, means for carrying and means for driving them; a car arranged below the bottom and supporting the middle of said three propellers, a separate rear car also arranged below the bottom of the airship body, a propeller at, and a motor in, this car, and a separate rear vertical rudder at the tail of the said body behind said latter car, substantially as set forth.

In testimony whereof I affix my signature.

JOSEF SCHULZ.
